STAND FOR STRAPPING MATERIAL OR THE LIKE

Charles R. Johnson, Jr., West Chester, Pa., assignor to American Viscose Corporation, Philadelphia, Pa., a corporation of Delaware

Filed July 27, 1961, Ser. No. 66,095

Term of patent 14 years

(Cl. D41—1)

FIG. 1 is a side elevational view of the stand for strapping material or the like showing my new design;

FIG. 2 is a front elevational view thereof; and

FIG. 3 is a fragmentary sectional view taken along the line III—III of FIG. 1.

The broken-line representation of a roll of strapping material in FIG. 1 is for purposes of illustration only.

I claim:

The ornamental design for a stand for strapping material or the like, as shown and described.
